UNITED STATES PATENT OFFICE.

MILTON R. EVANS, OF WASHINGTON, DISTRICT OF COLUMBIA.

FOOTREST.

1,321,903.

Specification of Letters Patent. Patented Nov. 18, 1919.

Application filed July 3, 1918. Serial No. 243,104.

To all whom it may concern:

Be it known that I, MILTON R. EVANS, a citizen of the United States, residing at Washington, in the District of Columbia, 5 have invented certain new and useful Improvements in Footrests, of which the following is a specification.

This invention relates to foot rests, and it relates particularly to articles of this kind 10 for use in supporting the feet of a person while having their footwear polished.

The primary object of the invention is to provide foot rests of the kind referred to, so constructed and arranged that they may 15 readily be moved out of the way as a person assumes or leaves a position to use the rests, thus avoiding possibility of colliding with the rests or of catching clothing on them before or after their use. A further object of 20 the invention is to provide foot rests capable of being moved out of the way when not in use and which shall be so formed as to facilitate the cheap and convenient arrangement of a number of the rests adjacent to a corresponding 25 number of chairs or seats.

With this object in view the invention consists of foot rests having the generic and specific features of construction and arrangement of the parts, substantially as 30 hereinafter described and claimed.

The invention is illustrated in the accompanying drawing in which:—

Figure 1 is a perspective view showing two chairs with foot rests arranged adjacent 35 thereto one set of foot rest being in position for use and the other set having the greater portion thereof concealed;

Fig. 2 is a side elevation of a foot rest, the guide plate used in connection therewith 40 being shown in section;

Fig. 3 is a view similar to Fig. 2, the foot rest being shown in position for use; and,

Fig. 4 is a perspective view of the bearing 45 and support of the foot rest.

The form of the invention herein illustrated involves the use of a shank to which a foot piece is attached, a guide by which the shank is directed to bring the foot piece into and out of position for use, and means 50 for moving and securing the shank. The shank 1 is of a length adapting it to move the foot piece 2 from a position below a seat to be occupied by a person having their footwear polished, into a position convenient 55 to form a rest for the foot of the user. As

herein shown the shank is curved and projects through an opening in a guide 3, which guide may be of any suitable form as for instance a plate of metal, attached to the side of a raised platform 4, and having 60 therein openings 5 of a size slightly larger than that of the shank, and conforming to the shape thereof. Preferably the shanks and foot pieces are arranged in pairs in order that both feet of a user may be supported. 65

Arranged beneath the platform 4 is a shaft 6 from which projects an arm 7 to which is pivotally connected the shank 1 of the foot rest. Also projecting from the shaft 6 is an arm 8 to which is attached an operating bar 9 which is adapted to move through an opening 10 in the plate 3 and has therein notches 11 of a size to receive the lower edge of the opening 10. In the use of the device the operating bar 9, assuming the parts to be in the position shown in Fig. 2 of the drawing, is released from engagement with the plate 3 and the bar is drawn outward until the plate is opposite 80 the rear opening 11. This movement of the operating bar moves the shank through the opening 5 thus bringing the foot rest 2 into a position to receive the foot of the occupant of a seat on the platform 4. When a person 85 is approaching or leaving the seat the operating bar is moved rearward carrying the shank out of the way and leaving exposed only the foot rest which lies along the front of the platform and offers no obstruction. 90

In order to adapt the device for use with a number of seats the shaft 6 is hollow and is arranged on a shaft 12 which extends the entire length of a platform occupied by such seats. Each shaft 6 is capable of independent rotation, and is secured in place on the shaft 12 by collars 13 attached to the shaft 12 by binding screws. 95

I claim:—

A foot rest comprising a shank curved 100 throughout uniformly and having a foot rest thereon, a guide having an opening conforming in size and shape to the shank and through which the latter extends, an operating bar connected to the shank, and means 105 whereby the operating bar is locked to maintain the foot rest at different elevations.

In testimony whereof I affix my signature.

MILTON R. EVANS.
